UNITED STATES PATENT OFFICE.

EMERSON P. JENNINGS, JR., OF LEHIGHTON, PENNSYLVANIA.

RULING DEVICE FOR PRINTING-PRESSES.

1,279,872.

Specification of Letters Patent. Patented Sept. 24, 1918.

Application filed May 7, 1914. Serial No. 836,845.

To all whom it may concern:

Be it known that I, EMERSON P. JENNINGS, Jr., a citizen of the United States, residing at Lehighton, in the county of Carbon and 55 State of Pennsylvania, have invented certain new and useful Improvements in Ruling Devices for Printing-Presses, of which the following is a specification, reference being had therein to the accompanying drawing.

- 10 This invention relates to ruling devices for printing presses and the object of the invention is to provide a printing press with an intermittently operable ruling device, the operation of which will be controlled by a 15 moving part of the press. To this end it is a further object of the invention to mount on a press a series of ruling pens movable into and out of engagement with the paper which is being fed through the press; to provide a 20 trip device to control the movement of said pens; and to operatively connect said trip device with the feeding mechanism of the press.

In the accompanying drawings, Figure 1 25 is a plan view of one end of a feeding mechanism for a printing press showing the invention applied thereto; Fig. 2 is a side elevation of such a feeding mechanism; Fig. 3 is an end elevation of the same; Fig. 4 is an 30 elevation of that side of the feeding mechanism opposite that shown in Fig. 2; and Fig. 5 is a detail of the adjustable cam.

In these drawings I have illustrated one 35 embodiment of my invention and have shown the same as applied to a feeding mechanism forming part of a reciprocating bed-and-platen press, but it will be understood that the invention is applicable to presses of various kinds and that the invention 40 itself may be modified to accommodate it either to differences in presses or to other conditions which may arise.

In these drawings I have shown at 1 a 45 portion of the frame of a press. Mounted in that portion of the frame here shown is a feeding mechanism which comprises a positively driven feeding roller 2 and a pressure roller 3 adapted to engage a web of paper 4 and draw the same through the press, where 50 it will be acted upon by the printing couple,

not here shown, and carry the web over a suitable supporting device, such as a bed-plate 5, and deliver the same to cutting mechanism 6. The feeding rollers in this particular form of feeding mechanism are 55 driven intermittently and to this end the feeding roller 2 has loosely mounted on its shaft 7 a gear 8, to which is rigidly secured a ratchet wheel 9 adapted to coöperate with a pawl 10 carried by a disk 11 rigidly secured to the shaft. This clutch connection causes the shaft to be rotated only when the gear 8 is moved in one direction. Movement is imparted to the gear by a segmental rack 12 pivotally mounted at 13 on the frame 1 60 and having a longitudinal slot 14 in which is mounted a slide block 15 having journaled therein a wrist pin 16 which, in turn, is mounted upon a disk 17. The wrist pin is preferably adjustable on the disk to enable 65 the amount of movement of the segment to be regulated. This is accomplished by mounting it in a transverse slot or groove 18. This particular type of feeding mechanism, however, does not form a part of the present 70 invention but is shown, described and claimed in an application for patent filed by me Feb. 9, 1914, Ser. No. 817,567. The disk 17 may be actuated in any suitable manner. In the present instance I have shown the 75 same mounted on a shaft 19 journaled in the side members of the frame 1 and having secured thereto a sprocket wheel 20 by means of which it is operatively connected with a moving part of the press. The cutting 80 mechanism 6 is actuated by means of eccentric rods 21 mounted on eccentrics 22 carried by a shaft 23 on which is mounted a sprocket wheel 24 which is driven by a sprocket chain 25 from a sprocket wheel 26 85 on the shaft 19.

The ruling device comprises a series of pens 27 disposed above the paper supporting bed plate and carried by a shaft 28 rotatably mounted on the opposite side members 1 of 90 the frame. These pens are of the ordinary kind and may be of any suitable number and arrangement. Extending into the pens 95 is a strip of felt or other suitable material, 29, which extends into a supply receptacle 100

30 and feeds the ink to the pens. The pens are adapted to engage the paper intermittently, the length of time which they remain in engagement with the paper and, 5 consequently, the length of the line, being adjustable. To control the operative engagement of the pens with the paper I have provided an actuating device which is controlled by a movable part of the printing 10 press and preferably is directly connected with the feeding mechanism. In the present instance, the shaft 28, which is a rock shaft, has loosely mounted thereon an arm, or lever, 31 which projects both to the front 15 and to the rear of the shaft. Rigidly secured to the shaft and also projecting from the front and rear thereof is a second arm or lever 32. To cause these parts to move in unison I have mounted in the upper arm, on 20 opposite sides of the shaft 28, screws 33 which engage the adjacent portions of the lever 31 and thus form a rigid but adjustable connection between this lever and the lever 32. The forward portion of the upper 25 lever 32 is also provided with a second screw 34 adapted to engage a plate 35 carried by the frame 1 and limit the downward movement of the lever 32 and, consequently, limit the pressure with which the pens are held in 30 engagement with the paper. Any suitable means may be provided for moving the pens toward the paper but, in the present construction, the weight of the longer ends of the lever and the parts carried thereby is 35 ample for this purpose and will serve to hold the pens normally in engagement with the paper. To move the pens out of engagement with the paper I provide a trip lever and a cam. The trip lever is here shown 40 at 36, is pivotally mounted on the frame 1 and has two arms, one of which is upturned as shown at 37, to engage the lever 31, one end of the lever being turned down, as shown at 38, to facilitate this contact. The 45 second arm 39 of the lever 36 is arranged to be engaged by the periphery of a cam 40. The engagement of the cam with the arm of the lever will raise the pens out of contact with the paper and retain the same 50 out of such contact until the raised portion of the cam has passed the trip lever, and the length of the lines will correspond to the distances between the raised portion and the pens. In order that the length of the 55 lines may be varied I have provided a cam 40 with a disk like body portion 41 having therein two grooves 42 in which are mounted a plurality of segmental cam plates 43. The body portion 41 is provided with a series 60 of holes 44 to receive bolts 45 which extend through the cam plates 43 and by means of which these plates may be secured in adjusted positions.

While I have shown and described one

embodiment of my invention it will be 65 understood that this has been chosen for the purpose of illustration only, and that I do not desire to be limited to the details of construction shown and described, for obvious modifications will occur to a person 70 skilled in the art.

Having thus fully described my invention, what I claim as new and desire to secure by Letters Patent, is:—

1. In a printing press, the combination 75 with a frame, a paper supporting device carried by said frame, and mechanism mounted on said frame to feed a web of paper through said press and over said supporting device, of a ruling device comprising a rock shaft 80 mounted on said frame, pens mounted on said shaft above said supporting device, and adapted to be moved into and out of contact with the paper thereon by the movement of said shaft, an arm rigidly secured 85 to said shaft, a second arm loosely mounted on said shaft, means for retaining said arms in adjusted positions relatively one to the other and for limiting the movement of said shaft in one direction, a trip lever pivotally 90 mounted on said frame and arranged to engage one of said arms, and a cam connected with said feeding mechanism and having adjustable cam surfaces to engage said trip lever and actuate said rock shaft. 95

2. In a printing press, the combination, with a frame, feeding rollers mounted in said frame, actuating mechanism for one of said feeding rollers mounted on said frame and comprising a shaft, of a second shaft 100 mounted on said frame, a series of ruling pens carried by said second shaft, an arm loosely mounted on said shaft, a second arm rigidly secured to said second shaft, set screws extending through said second arm 105 on opposite sides of said second shaft and engaging corresponding portions of said first arm, means to limit the movement of said second arm, a trip lever pivotally mounted on said frame and adapted to engage said 110 first arm, and a cam having adjustable surfaces mounted on the shaft of said feeding mechanism and adapted to actuate said trip lever.

3. In a ruling device, a shaft, ruling pens 115 carried thereby, an arm loosely mounted on said shaft, a second arm rigidly secured to said shaft, means for retaining said arms in adjusted positions relatively one to the other and for limiting the movement of said 120 shaft in one direction, a trip lever arranged to engage one of said arms, and a cam arranged to engage said trip lever and actuate said shaft.

4. In a ruling device, a shaft, ruling pens 125 carried by said shaft, an arm loosely mounted on said shaft, a second arm rigidly secured to said shaft, set screws mounted on

one of said arms on opposite sides of its axis and arranged to engage the corresponding portions of the other arm, means to limit the movement of said shaft in one direction, a 5 trip lever arranged to engage one of said arms, and a cam having adjustable surfaces to engage and actuate said trip lever.

Copies of this patent may be obtained for five cents each, by addressing the "Commissioner of Patents, Washington, D. C."

In testimony whereof, I affix my signature in presence of two witnesses.

EMERSON P. JENNINGS, JR.
